RAILWAY DRAFT APPLIANCE

Hal E. Vickerman, Milwaukee, Wis., assignor to A. O. Smith Corporation, Milwaukee, Wis., a corporation of New York

Filed May 27, 1963, Ser. No. 283,320

14 Claims. (Cl. 213—8)

This invention relates to a draft appliance of a railway car and more particularly relates to a draft appliance having a self-contained or unitary construction.

Railway cars and freight cars in particular are subjected to a large number of shock forces during operation. These shock forces are imposed on the couplers at the ends of the car and are either in buff or draft, a buff force being one which is directed inwardly against the coupler while a draft force is directed oppositely thereto or outwardly of the coupler.

Normally, the shock forces of the greatest severity occur in buff and result from the practice of coupling cars to one another by effecting a heavy sudden impact between cars to enable their couplers to engage and automatically interlock. Thus, for example, when assembling cars to form a train, individual cars may be rolled down a suitable incline toward a standing car or line of cars of the train to effect coupling.

The coupling of the cars may also be effected by bumping the cars together by means of a prime mover or engine. These coupling forces attain very substantial proportions and are capable of causing severe damage to the car, its couplers, and the car contents, if any.

Other, though normally less substantial buff forces as well as draft forces occur in and between the cars which are part of a moving train. These forces are due in part to the fact that a certain amount of slack motion is provided in the car couplers. During starting and acceleration of the prime mover or engine of the train and during leaving a curve and on entering an up grade, the individual cars of the train tend to stretch apart and each car is subjected to a heavy jerk or draft force by the faster traveling car immediately ahead of it the instant the slack is removed from their couplers. The severity of the draft force increases progressively from the front to the rear of the train and in a long train, the rear cars may be subjected to a fairly substantial shock force. In a similar manner, during stopping and deceleration of the prime mover and on entering a curve and on a down grade, the cars of the train bunch or crowd together and each car is subjected to a buff force by the faster moving car to its rear when the slack is taken out of their couplers. In this case, the magnitude of the force increases progressively from the rear to the front of the train.

The present invention is directed to a draft appliance which is fully capable of taking up and absorbing shock forces imposed on a coupler of a railway car and more specifically is directed to a draft appliance in which the component parts thereof are arranged and interconnected to form a self-contained assembly adapted to be mounted within a railway car center sill in supporting relation with the coupler.

In accordance with the invention, the proposed draft appliance is comprised of a coupler receiver assembly adapted to be connected to a coupler of a car, a two-way acting shock absorber connected to the coupler receiver assembly for absorbing forces imposed on the coupler, and a resilient return means connected to the coupler receiver assembly and urging the latter and the shock absorber unit to normally neutral positions. The coupler receiver assembly includes a housing formed with longitudinally spaced external abutment surfaces and which are adapted to engage similarly spaced abutment surfaces

2

formed within a center sill of a railway car to secure the housing longitudinally of the sill. A coupler adapter block is mounted for forward and rearward sliding movement relatively of the housing and has means to receive a car coupler and means adapted to be releasably connected with the coupler to support the same longitudinally of the sill. The block and housing are formed with longitudinally spaced stop surfaces cooperating to limit forward and rearward movement of the block in the housing and which serve to take up and transmit any unabsorbed portion of a coupler force directly into the sill.

In accordance with a preferred construction, the coupler block is provided with replaceable wear plates on pre-selected of its surfaces and similar wear plates are provided on the corresponding surfaces of the housing and sill to provide slide surfaces for the block which are replaceable. The plates desirably have a high wear resistant characteristic to reduce frictional wearing therein.

The shock absorber in a preferred form of the invention 20 consists of a hydraulic piston-cylinder unit connected through its cylinder member to the inner end of the housing of the coupler receiver assembly. The piston of the hydraulic unit is connected by an operating rod to the coupler adapter block and is opposed for sliding movement in the cylinder to effect damping of coupler forces by the restricted flow or displacement of hydraulic fluid through a number of axial grooves provided in the cylinder. To prevent fluid cavitation in the unit when the piston is caused to accelerate rapidly in the cylinder by a heavy, sudden shock force on the coupler, a fluid return means is secured exteriorly of the cylinder between the opposite ends thereof. The fluid return means is in fluid communication with the ends of the cylinder by valved openings which are adapted to be actuated upon a pre-determined pressure differential between the cylinder and return means to allow fluid to surge into the cylinder from the return means in sufficient quantity to prevent any appreciable cavitation in the cylinder fluid. Excessive pressure buildup in the hydraulic unit is prevented by pressure relief valves which in accordance with the invention are disposed directly within the piston to provide direct fluid flow from the high pressure side of the cylinder to the low upon actuation of the relief valves. These valves have a compact construction, a high fluid handling capacity and are quick opening and closing.

The fluid orificing set forth enables an exceptionally compact construction for the hydraulic unit and is capable of highly efficient and reliable functioning under all load conditions.

50 Another novel aspect of the invention relates to the connection between the operating rod of the hydraulic unit and the coupler block. This connection is preferably effected by a ball and socket joint to relieve the rod of bending loads as forces are transmitted thereto from the block. In accordance with the invention, the elements of the joint are vertically slidably assembled in a recess in the coupler block and the recess is shouldered to retain the elements to the block so as to permit the block and rod to be readily slipped apart when it is desired to service the hydraulic unit.

65 The resilient return means is connected between the housing and coupler adapter block and includes oppositely acting resilient elements yieldingly maintaining the block in an intermediate or neutral slide position in the housing. Upon displacement of the block in either direction from neutral as by a shock force on the appliance, the resilient elements are energized and upon load release reposition the block in the neutral position. The shock absorber mechanism is automatically repositioned in a corresponding neutral position at the same time.

70 It is contemplated to employ either a single or double set of resilient elements mounted along the underside of

the coupler receiver assembly or in the alternative a double set of elements mounted one each along the sides of the coupler assembly in outboard relation with the sides of the center sill. In accordance with another aspect of the invention, the resilient elements are mounted on elongated rods which are telescopically extensible and retractable. The telescopic form of the rods enables a highly compact overall construction for the resilient return means and is particularly advantageous where it is desired to mount the return means on the underside of the coupler receiver assembly in applications wherein only a limited space is available thereat due to the configuration of the railway car.

The proposed unitary draft appliance of the invention is secured longitudinally of the center sill of the car solely by means of the abutments formed in the housing of the coupler receiver assembly and in the sill itself. Vertical support is provided by means of brackets attached across the bottom of the sill beneath the housing of the coupler receiver assembly and the hydraulic shock absorber unit by mounting bolts. The bracket may be formed as an integral part of the appliance or as separate and distinct members as desired. The various parts of the appliance are otherwise free of attachment to the sill and are designed and arranged to permit the appliance to be installed within or removed from the sill without presenting any interference thereto. Maintenance, repair, and/or replacement procedures are greatly simplified and facilitated by this construction.

With the present construction, the sill within which the appliance is mounted is in no way subject to wear from friction during operation due to the self-contained form of the coupler receiver assembly. Further, the problem of frictional wear in the proposed appliance is largely alleviated due to the utilization of the wear plates on those parts which are slideable with respect to one another. The present construction is of further important advantage in that any unabsorbed portion of a coupler force is transmitted into the sill of the car via the coupler block and the fixed housing, thus avoiding direct impact between the sill and related parts of the coupler and appliance and precluding objectionable brinelling, coining, swaging and the like of the sill. Moreover, in the present construction, built in mechanical stops are provided for limiting coupler block sliding movement when subjected to buff and draft shock forces and hence the range of such movement can be controlled by the appliance manufacturer.

When the draft appliance is to be used with a long shank coupler, the coupler receiver assembly is modified in construction to meet added code and industry requirements for the long shank coupler. For example, by code such couplers are required to be supported vertically intermediate the ends to reduce the moment arm in the coupler for downwardly directed loads. This is achieved in the present invention by modifying the front of the coupler block to include a deck-like support platform within which is resiliently mounted a vertically reciprocal bearing plate. The deck is designed such that with a coupler attached to the block, the bearing plate engages and supports the coupler adjacent the front end of the latter.

In some applications, it is desired that the long shank coupler be centered automatically in the sill when free of connection with the couplers of other cars to facilitate coupling of the cars. For this purpose, it is proposed to incorporate a spherical bearing assembly in the coupler block to seat the rear end of the coupler and which includes a rocker member movable as a unit with the coupler with horizontal swing movement thereof. The rocker member is normally urged to a centered position in the coupler block and the coupler to a centered position in the sill by a pair of resilient elements contacting the member on either side of center. These elements are selectively energized as the coupler swings to either side of center and act on the rocker member to return the

coupler to center when the latter is free of connection with another coupler.

Other objects and advantages of the present invention will appear in the course of the detailed description of the invention appearing hereinafter.

The accompanying drawings illustrate the best mode presently contemplated of carrying out the invention.

In the drawings:

FIG. 1 is a plan view of a portion of a draft appliance embodying the present invention in operative relation within the center sill of a railway car, some parts being broken away and others being shown in section;

FIG. 1a is a view taken on line 1a-1a of FIG. 1;

FIG. 2 is a vertical axial section of the draft appliance of FIG. 1, certain parts being shown in elevation;

FIG. 3 is a view of the front end of the draft appliance taken on the lines 3-3 of FIG. 1, with parts of the retaining structure for the draft key being broken away and others sectioned for clarity of illustration;

FIG. 4 is an enlarged fragmentary side elevation of the draft key retaining structure taken along the lines 4-4 of FIG. 3.

FIG. 5 is a horizontal sectional view of the front end of the draft appliance shown in FIG. 1 illustrating the parts in a full pull out position;

FIG. 6 is similar to FIG. 5 illustrating the parts in a fully inward position;

FIG. 7 is a vertical axial sectional view on an enlarged scale of a hydraulic piston-cylinder unit embodied in the present draft appliance with the piston shown in a neutral position within the cylinder in the full lines and at the limits of buff and draft movement in the phantom lines, certain parts being shown in elevation and other being broken away;

FIG. 8 is a vertical transverse sectional view of the piston-cylinder unit taken along the lines 8-8 of FIG. 7;

FIG. 9 is a view similar to FIG. 8 only taken on the lines 9-9 of FIG. 7;

FIG. 10 is similar to FIGS. 7 and 8 only on a reduced scale and taken on the lines 10-10 of FIG. 7;

FIG. 11 is a vertical axial section of a fluid volume compensator which is attached to the hydraulic piston-cylinder unit of the appliance;

FIG. 12 is a perspective view of an end portion of a railway car center sill having a standard construction;

FIG. 13 is a perspective view of the portion of the sill shown in FIG. 12 modified to receive a separate cast extension to render the sill suitable for receiving the draft appliance of the invention;

FIG. 14 is an axial vertical sectional view of a modified form of the draft appliance of the invention with a part of a sill and a coupler being shown in phantom to illustrate the general relationship of the parts to one another;

FIG. 15 is a plan view of the draft appliance shown in FIG. 14 with some parts being broken away and others being sectioned;

FIG. 16 is a side elevation of the draft appliance shown in FIGS. 14 and 15 with the sill and coupler being omitted;

FIG. 17 is an elevational view of the front of the modified draft appliance taken on the lines 17-17 of FIG. 14;

FIG. 18 is an elevational view of the rear of the modified draft appliance taken on the lines 18-18 of FIG. 14;

FIG. 19 is a fragmentary vertical sectional view of a modified form of the draft appliance shown in FIGS. 1 to 11, illustrating an alternative arrangement and construction of the return spring assembly;

FIG. 20 is a front end elevational view of the structure shown in FIG. 19;

FIG. 21 is a rear end elevational view of the structure of FIG. 19;

FIG. 22 is a fragmentary vertical axial view, partly in section and partly in elevation, of a modified form of the draft appliance shown in FIGS. 14 to 18, illustrating an

alternative construction for the return spring assembly; and

FIG. 23 is a front end elevational view of the structure of FIG. 22.

The form of the invention illustrated in FIGS. 1 to 11 of the drawings is designed for use with railway cars of from 50 to 60 feet in length and which are equipped with the A.A.R. standard "E" type coupler as opposed to the long shank A.A.R. alternate standard "E" type coupler and the A.A.R. standard "F" type coupler which are used on cars exceeding 60 feet in length. Referring more particularly to FIGS. 1 to 4, the unitary draft appliance 1 of the invention is shown operatively disposed within a railway car center sill 2 which extends longitudinally and forms a part of a railway car (not shown) in accordance with known construction. Sill 2 has an inverted generally channel cross-sectional configuration including the opposed parallel side walls 3 having the outwardly flanged lower edges 4 and an upper or top wall 5 spacing the side walls 3. The sill is open at the front end 6 and a coupler 7 is supported in forwardly projecting relation therefrom by the draft appliance whereby shock forces imposed on the coupler in operation are transmitted to and absorbed by the appliance to cushion the coupler and the car from shock. It will be understood that a second draft appliance and coupler are similarly disposed in the other extremity of the center sill at the opposed end of the railway car.

The illustrated draft appliance 1 is formed generally of a self-contained coupler receiver assembly 8 connected to coupler 7 to support the same in sill 2, a two-way acting hydraulic shock absorber 9 connected to the inner end of coupler receiver assembly 8 for effecting dissipation of shock forces imposed on coupler 7 and coupler receiver assembly 8, and a return spring assembly 10 connected to coupler receiver assembly 8 in outboard relation with the opposed sides 3 of sill 2 and urging the coupler assembly and the shock absorber unit to neutral positions.

Coupler receiver assembly 8 includes a channel-section housing member 11 disposed longitudinally of the sill in upwardly opening relation thereto. The side walls 12 of housing 11 are offset inwardly immediately adjacent the forwardmost end of the sill 2 and define a pair of external vertical abutments 13 at the rear edge thereof. Rearwardly, housing member 11 is closed by a heavy gauge open-topped end wall 14 the rear face of which defines a rear vertical abutment 15 spanning the housing 11. The portion of sill 2 receiving housing 11 is formed to complement the outer configuration thereof with a front and rear abutment surface 16 and 17 respectively provided within each sill side wall 3 in direct engagement with the corresponding abutment 13 and 15 of housing 11 to thus releasably secure the housing longitudinally of the sill 2. As most clearly shown in FIGS. 1, 2 and 4, housing 11 is supported vertically within sill 2 by a bracket 18 extending between and secured to the opposed flanges 4 of sill side walls 3 as by a number of mounting bolts 19. A number of shims 20 are interposed between the ends of bracket 18 and the flanged edges 4, as in the illustrated construction, the housing extends below the level of the sill. As will be more fully described hereinafter, an additional bracket 21 is similarly secured to sill flanges 4 beneath hydraulic unit 9 to support the rear of the appliance vertically in sill 2.

Coupler receiver assembly 8 further includes an elongated coupler adapter block 22 mounted for sliding movement longitudinally of housing 11. The front of block 22 projects from the housing and sill through open end 6 and as will be more fully explained hereinafter receives and connects to coupler 7 through the front end to support the coupler for sliding movement in the sill. In order to limit block movement in the housing and in turn limit coupler movement in the sill when subjected to a buff or draft force, the rear end of block 22 is widened or offset laterally as indicated at 23 and the housing is

provided with a correspondingly widened interior portion extending from housing end wall 14 to a point just to the rear of the aforescribed external abutment 13 to accommodate enlargement 23. Block enlargement 23 provides on its front face a pair of vertically extending stop surfaces 24 which are adapted to engage the complementary shaped vertically extending abutment or stop surfaces 25 formed interiorly of housing 11 at the front of the enlarged or widened portion thereof to thus limit forward movement of the block in the housing 11. Similarly, the rear face 26 of block enlargement 23 cooperates with the front face 27 of the housing end wall 14 which forms a vertically extending abutment or stop surface to limit rearward movement of the block in housing 11.

For purposes of maintaining the block in proper sliding engagement with housing and to reduce the problem of wearing in the block and the corresponding surfaces of the housing and sill from the effects of friction, the present invention contemplates providing the bottom and top surfaces of block 22 with the relatively thin wear plates 28 and 29 respectively. Plates 28 and 29 are preferably composed of steel alloy or other suitable metal having a high wear resistance characteristic. Similar wear plates 28' and 29' are secured to the inside of the housing bottom wall 30 and to the inside of sill top wall 5 respectively and cooperate with the corresponding plates 28 and 29 to take up frictional wear from the surfaces which they cover. It has been found that frictional wear in the sides of the block and the corresponding sides of housing 11 is negligible, accordingly, these surfaces are not provided with wear plates.

Wear plate 28' is preferably secured to housing wall 30 by a number of locator pins 31 provided interiorly of the wall and which register with and fit within suitable openings in the plate to enable the ready replacement of the plate when worn. In addition, wear plate 28' is preferably symmetrically formed and locator pins 31 are disposed to permit plate 28' to be reversed and/or inverted with respect to the housing if locally worn, thus increasing the life of the plate. The other of the wear plates 28, 29 and 29' may be secured as by welding or the like and when worn are cut off and replaced. The provision of wear plates on the aforementioned surfaces enables block 22 to be maintained in close sliding engagement within housing 11 for long periods of operation as well as permitting ready, inexpensive means for renewing contacting surfaces when worn to a predetermined extent.

Referring now to the mounting of coupler 7 in coupler block 22, the latter is provided with a generally rectangular longitudinally extending chamber 32 opening at the front of the block. The opposed sides of chamber 32 are each formed with an inwardly extending, horizontal key guide 33 having the slots 34 to support a transverse draft key 35. The slot 34 in the right-hand key guide 33 as viewed in FIG. 3 is extended all the way through to the corresponding right-hand side of block 22 to permit key 35 to be inserted within and removed from the key guides through the block proper. The slot 34 in the left-hand key guide 33 has a blind construction save for a knock out opening 36, the purpose of which construction will appear.

Coupler 7 is formed with the coupler jaws 37 adapted to interlock with the coupler of another car and has an elongated, tapered shank 38 which is provided with a transverse slot 39 at the end opposite jaws 37. Coupler shank 38 extends rearwardly within the chamber 32 in coupler block 22 with slot 39 receiving draft key 35 held in key guides 33 to thus connect the coupler to the block.

To retain draft key 35 captive between block 22 and coupler shank 38, right-hand slot 34 is enlarged vertically as shown and is formed along its lower outer edge with a raised lip or shoulder 40. Draft key 35 is of a length such that when assembled in the block the right end of the key abuts shoulder 40. A retainer plate 41 is slid-

ably assembled in the right-hand slot 34 in overlying relation with the upper right-hand end of key 35 as viewed in FIG. 3 to hold key 35 in positive seated relation against shoulder 40. The exterior right side of coupler block 22 is grooved from the top of the block to a point just above the corresponding right-hand slot 34, as shown in FIG. 4, to form a ledge-like projection 42 in the side of the block. A locking pin 43 is inserted vertically through portion 42 and through the outer end of the retainer plate 41 as shown to hold the latter firmly against draft key 35, thus releasably securing the draft key between the coupler block and coupler. A cotter key 44 is inserted through locking pin 43 immediately below plate 41 to hold the pin in place.

To remove draft key 35 from block 22, cotter key 44 is initially withdrawn and first locking pin 43 and then retainer plate 41 are removed. Draft key 35 is then pried up to clear the shoulder 40 by any suitable lever, such as a screw driver. Then, working from the left-hand side of the block 22, a suitable pin, not shown, is inserted through knock out opening 36 and the draft key 35 is driven out of the coupler block 22 by a hammer or other suitable means. This removal procedure may be performed quite readily, enabling the coupler 7 to be rapidly disconnected from block 22 as may be required for purposes of replacement of a broken or damaged coupler. The reinsertion of draft key 35 within block 22 to reconnect a new coupler thereto is also a relatively fast, simple procedure with the construction of the present invention.

Coupler 7 and coupler adapter block 22 are designed and constructed to permit coupler 7 to pivot through a limited arc with respect to coupler block 22 and in both the horizontal and vertical as the car with which the appliance is being employed traverses a curve or grade in the track. For this purpose, coupler slot 39 is formed somewhat wider and deeper vertically than draft key 35. Additionally, the rear edge 45 of shank slot 39 is formed with a convex surface contour which engages the corresponding rear edge 46 of draft key 35 when coupler 7 is pulled fully forwardly in block 22 under application of a draft force to accommodate pivotal movement of coupler 7 in the full pull out position. This position of the parts is shown in FIG. 5 of the drawings.

In the fully inward position of coupler 7 in block 22, as shown in FIG. 6, the rear end of the coupler shank 38 is in abutment with the rear end wall 47 of chamber 32 in coupler block 22, and the front edge 48 of shank slot 39 is spaced from the corresponding front edge 49 of draft key 35, this relationship resulting by making the distance between shank front and rear surfaces 48 and 45 respectively less the width of the draft key 35 greater than the distance from the rear end of coupler shank 38 to chamber end wall 47 with coupler 7 in full pull-out position. Thus positioned, coupler 7 may pivot on chamber rear end wall 47.

In addition to the above measures, a limited clearance is provided between coupler shank 38 and key guides 33. A similar but much greater clearance is also provided between the front end of shank 38 and the sides of chamber 32 at the front end thereof to accommodate pivotal movement of the coupler in the block.

As best viewed in FIG. 2, coupler 7 is supported for horizontal swing motion in block 22 by a raised shoulder 50 formed integrally with block 22 at the entrance to chamber 32. A wear plate 51 is positioned on shoulder 50 to prevent rapid wearing of the supporting surface.

Referring again to FIG. 6 of the drawings, coupler block 22 is shown in the rearmost slide position relative to housing 11, this position being fixed by stop surfaces 26 and 27 formed on block 22 and housing 11 respectively as previously described. In this position, coupler jaws 37 are spaced forwardly of the end of center sill 2, thus precluding objectionable coining, swaging and the like.

of the sill when the parts are forced fully inwardly under buff loads on the coupler.

The hydraulic shock absorber mechanism 9 which is attached to the inner end of coupler receiver assembly 8 for dissipating coupler forces is shown herein as a piston-cylinder assembly. See FIG. 2. The attachment of mechanism 9 to coupler receiver assembly 8 is effected between housing rear end wall 14 and the cylinder 52 of the assembly 9. To this end, the wall 14 is provided with a central aperture 53 which is counterbored as shown in FIGS. 1 and 7 to form an arcuate retaining shoulder 54 partially surrounding the aperture 53. Cylinder 52 is disposed within aperture 53 in endwise abutting relation with shoulder 54 and is secured to wall 14 as by a weld laid between the contiguous surfaces of the cylinder and wall.

A piston 55 having an associated operating rod 56 is mounted for sliding movement in cylinder 52 between the cylinder front and rear heads 57 and 58 respectively. Operating rod 56 extends through cylinder front head 57, with suitable bearing support and packing provided in the head to seal the rod thereto, and is attached at its front end to the rear of coupler adapter block 22, thereby connecting the shock absorber unit 9 to the block. The attachment is preferably effected through a ball-and-socket joint to enable the block and rod to float or pivot universally with respect to one another in the event of any longitudinal misalignment therebetween to relieve the rod of bending loads from coupler forces transmitted thereto from the block 22. In the present invention, the ball-and-socket connection is of single surface construction being designed to permit adjustment between rod 56 and block 22 in the buff direction of loading only, and as will now be described, is fashioned in a manner enabling convenient and rapid disassembly of the rod from the block. The front end of rod 56 is threadably connected to a ball or knuckle 59 formed over its front face with a segmental spherical convex surface contour. A dowel pin 60 is provided to prevent knuckle 59 from working loose on the rod 56. The rear end of coupler block 22 is provided with a vertically extending recess 61 opening to the bottom and rear of block 22 and having a constricting lip or shoulder 62 formed on the periphery of the rear opening portion thereof. Knuckle 59 is adapted to fit upwardly within recess 61 and is releasably held therein by shoulder 62. The ball joint further includes a knuckle socket 63 formed complementary to the front face of knuckle 59 and releasably held in recess 61 in bearing relation with knuckle 59 by a coil spring 64 which is disposed in a horizontal opening 65 extending through the rear of the block 22 and opening at the front face of chamber end wall 47 previously described. Spring 64 is adjustably held in compression by a set screw 66 disposed in the opening 65 which is properly tapped therefor.

With the above construction and with appliance 1 removed from sill 2 and coupler 7 withdrawn from block 22 to detach operating rod 56 from block 22 it is only necessary to loosen set screw 66 working through the front end of block 22, and then slip knuckle 59 out through the bottom of recess 61. With rod 56 free of block 22, the rod 56, piston 55, and cylinder front head 57 are removable as a unit from cylinder 52 to enable servicing of hydraulic unit 9, the head 57 being secured in place as by a snap ring-groove arrangement.

In order to prevent dust and other foreign material from collecting on operating rod 56 and entering within and possibly interfering with the operation of hydraulic unit 9, rod 56 is enclosed between cylinder 52 and block 22 by a flexible boot and clamp assembly 67. Assembly 67 includes a flexible, bellows-like dust boot 68 disposed concentrically of rod 56. The front end of boot 68 is clamped to rod 56 just to the rear of adapter block 22 by a screw tensioned clamp ring 69, as clearly shown in FIGS. 1 and 2, while rearwardly dust boot 68 encircles an annular shoulder 70 on front cylinder head 57 and is

secured thereto by a second screw tensioned clamp ring 69.

Referring again to the construction of the hydraulic unit 9 and more specifically to the means by which coupler forces are dissipated, it will be understood that cylinder 52 is filled with a suitable hydraulic fluid medium. The fluid is adapted to be restrictively displaced in cylinder 52 in response to piston movement therein in either a forward or rearward direction through a series of axially extending, circumferentially spaced grooves 71 provided within the cylinder and being longer than the longitudinal extent of piston 55. In the illustrated construction, the grooves 71 are shown terminating at their front end in a common radial plane which is spaced from the cylinder front head 57 and have a varying axial length with the longest of the grooves terminating in spaced relation from rear cylinder head 58. Piston 55 is sealed to the cylinder 52 by a circumferentially extending seal ring 72 located intermediate a pair of piston wear rings 73 and is normally positioned in cylinder 52 so that it overlies grooves 71 and with its front face lying in the common radial plane of the grooves with seal ring 72 to the rear thereof as shown in FIG. 7. This position of the piston, referred to hereinafter as the neutral position, results from the action of return spring assembly 10 on coupler adapter block 22 in a manner which will be subsequently explained.

Assuming that with piston 55 in the neutral position, coupler 7 is subjected to an inwardly directed or buff force causing the piston to slide rearwardly in cylinder 52. The aggregate cross-sectional area of grooves 71 available for fluid displacement is greatest at the outset of piston movement and decreases progressively as piston 55 slides rearwardly in the cylinder owing to the aforesaid construction of grooves 71. At the same time, however, the initial force on hydraulic unit 9 drops off gradually due to the fluid opposition to piston movement. In accordance with the invention, the grooves 71 are arranged such that the cross-sectional area thereof decreases at a rate which results in a substantially uniform pressure within the hydraulic unit or as close thereto as reasonably possible over the major portion of its buff stroke for a given coupler force or range of forces. As a result of this construction the hydraulic unit 9 is capable of dissipating extremely heavy buff forces in a highly efficient and reliable manner.

With piston 55 in neutral position and caused to slide forwardly within cylinder 52 as by a draft force on coupler 7, the total cross-sectional area of grooves 71 is available for fluid displacement and remains available until piston ring 72 reaches the front terminus of the grooves to effect the desired damping of the force.

The rearward or forward movement of piston 55 in cylinder 52 corresponds to rearward or forward movement of block 22 in housing 11. The previously described system of mechanical stops between block 22 and housing 11 is designed to prevent piston 55 from moving rearwardly within cylinder 52 past the position shown in the right-hand phantom lines in FIG. 7. In this position, the piston 55 is spaced from cylinder rear head 58, thus preventing the piston from bottoming out in the cylinder and causing severe injury thereto. Similarly, in the case of forward movement of the piston, the stop surfaces of block 22 and housing 11 preclude piston movement beyond the position indicated in the left-hand phantom lines of FIG. 7 in which position piston 55 is spaced from cylinder front head 57.

To preclude excessively high fluid pressures in hydraulic unit 9 and resultant damage thereto upon a particularly severe draft or buff force on coupler 7, a pressure relief system is provided in the unit. In the illustrated construction, this system is in the form of a pair of buff relief valves 74 and a single draft relief valve 75 mounted directly in piston 55. A preferred valve construction is shown and hereinafter described to the extent

necessary to clearly describe the feature of the present invention. For a more detailed description, reference is made to a copending patent application of Charles O. Breitsprecher, entitled Relief Valve, Serial No. 131,391, filed August 14, 1961.

Valves 74 and 75 are of identical construction and operation and accordingly, for purposes of simplification, only one valve will be described in detail herein, it being understood, however, that valves 74 and 75 are mounted oppositely of one another in the piston. Referring to FIG. 7 of the drawings, the buff relief valve illustrated therein is comprised generally of a cylindrical valve body 76 removably fixedly secured within an axial opening 77 in the piston 55. A cylindrical valve member 78 is slidably disposed in valve body 76 and is formed at its front end and which corresponds to the low pressure side of the valve with a frusto-conically shaped valve head 79 seating against a ring 80, the ring being of beveled construction to define with the valve head 79 an annular fluid confining chamber 81. Valve member 78 is normally held seated on the ring 80 by a coil spring 82 assembled coaxially of the member 78 in an annulus formed between the latter and valve body 76. Valve head 79 is provided with a series of fairly large generally radially outwardly extending openings 83 establishing fluid communication between chamber 81 and the high pressure side or inner end of the relief valve. The fluid pressure on the high pressure side of the relief valve acts on valve member 78 through the exposed surface thereof in annular chamber 81 to force the latter to unseat against the bias of spring 82 and simultaneously urges the valve 78 to a closed position through the exposed surface area between openings 83.

The pressure responsive area on either side of valve member 78 is designed so that the effective area in annular chamber 81 is slightly greater than that between openings 83. Consequently, a given fluid pressure in cylinder 52 on the high pressure side of the relief valve results in a net effective force tending to force valve body 78 off ring 80 to open the relief valve. Normally, however, the valve body is maintained closed by coil spring 82. At some pressure level, however, and which is set to correspond to the maximum fluid pressure desired in hydraulic unit 9 in the buff direction of its stroke in the case of valves 74, the net effective force tending to unseat valve body 78 will exceed the bias force of spring 82 at which time the valve body will begin to open. As soon as valve member 78 cracks open, the effective pressure responsive area of the frusto-conical valve head 79 increases rapidly, adding to the effective valve opening force and enabling valve member 78 to rapidly fully open when the fluid pressure rises to the preselected valve.

In order to insure against any possible opening of the valve responsive to fluid pressure on the low pressure side thereof, valve head 79 is further provided with a number of passages 84 opening into annular chamber 81 between valve member 78 and valve body 76 from the low pressure side of the relief valve. Fluid is thus free to enter the chamber 81 and acts against an external shoulder 85 formed on valve member 78 to retain the latter tightly against ring 80. The pressure responsive area of shoulder 85 exceeds that of the face of valve head 79 exposed to the lower pressure side of the relief valve to provide this result.

If in operation the force on the draft appliance is sufficiently great to result in the fluid pressure in hydraulic unit 9 reaching the predetermined setting of either the relief valves 74 or 75, the corresponding relief valve or valves open and permit rapid fluid displacement from the high pressure side of the piston and cylinder to the low pressure side to relieve the pressure and prevent further pressure build-up. The relief valve or valves close when the hydraulic unit is in the full buff or draft position or at such times in the stroke of the unit when the pressure drops below the valve settings.

The location of the relief valves 74 and 75 directly

in the piston enables a direct flow of fluid between the high and low pressure sides thereof and more importantly enable an unencumbered construction within the hydraulic unit. Valves of the illustrated type are particularly well suited for the present invention because of their compact design and more importantly because of their quick opening action and high fluid handling capacity.

In order to prevent fluid cavitation in hydraulic unit 9 when piston 55 is caused to accelerate rapidly in cylinder 52 as by a particularly severe shock force on coupler 7, the hydraulic unit further includes a channel-section fluid return member 86 secured to cylinder 52 in longitudinally extending upwardly opening relation. As most clearly shown in FIGS. 8-10, member 86 corresponds generally in width to the inside width of sill 2 to the rear of sill abutment 17 and is divided into the separate longitudinal half-sections 87 by cylinder 52. The sides 88 of the fluid return member 86 are secured in fluid tight relation to cylinder 52 as by a weld laid the length of their adjacent surfaces. The bottom wall 89 of member 86 is in the plane of and abuts against the bottom wall 30 of housing 11 as shown in FIG. 7 and is secured thereto as by welding. At the front end of the fluid return member 86 and referring now to FIGS. 7 and 8, there is provided a pair of fillet-like end plates 90 welded to cylinder 52 and to the sides 88 and bottom 89 of the member 86 to seal the front end of the latter to the cylinder. In a similar fashion, a second pair of fillet-like plates 91 are provided at the rear end of member 86 and are welded to cylinder 52 to seal the rear end of the member thereto (see FIGS. 7 and 10). The front end of member 86 is in direct two-way fluid communication with the front end of cylinder 52 through means of a pair of static fluid orifices 92 provided in either side of cylinder 52 just to the rear of front head 57. Orifices 92 extend radially outwardly to each of the split sections 87 of member 86. A similar pair of static fluid orifices 93 is provided in the rear end of cylinder 52 to establish two-way fluid communication between the rear end of the cylinder and fluid return member.

In addition, each end of the return member 86 is in one-way fluid communication with the corresponding ends of cylinder 52 through inwardly opening valve controlled orifices as follows.

Front cylinder head 57 is provided with a circumferentially extending groove 94 and is sealed to the cylinder 52 by a pair of seal rings 95, one to each side of the groove. Groove 94 is in fluid communication with the fluid return member 86 through a pair of orifices 96 located in the lower half of cylinder 52 one to either side of center, and which open into each side 87 of member 86. Cylinder front head 57 is further provided with a valved recess 97 in its rear face and which is in fluid communication with groove 94 through an orifice 98. Recess 97 is closed by a check valve 99 located in a suitable annular groove provided in the rear face of head 57 as shown and which is secured to head 57 by a threaded pin 100. Check valve 99 includes a valve seat 101 mounted on pin 100 and which is resiliently urged against the head to normally close recess 97 to fluid passage by a coil spring 102 assembled co-axially of pin 100. A spring bearing plate 103 is mounted on pin 100 at the headed end thereof to seat the spring 102. With valve seat 101 lifted off cylinder front head 57, fluid communication is established between fluid return member 86 and cylinder 52 by way of orifices 96, groove 94, orifice 98 and recess 97.

Referring now to the rear end of the cylinder, a fluid volume compensator 105 which is welded to and encloses the rear head end 58 of cylinder 52 as will be more fully described hereinafter. An annular groove 106 is disposed on the circumferential surface of head 58 and a drilled opening 107 is extended diametrically therethrough. As best shown in FIG. 10, groove 106 is in fluid communication with the split segments 87 of fluid return member 86 by a pair of radial orifices 108. Drilled

5

opening 107 in turn is in fluid communication with the cylinder 52 to fluidly connect the fluid return 86 to cylinder 52 by a valved opening 109 in cylinder rear head 58. Opening 109 is normally closed to fluid flow by a check valve 99' which is substantially identical in construction and functioning to previously described check valve 99. In the case of check valve 99', however, retainer pin 100' is threadably secured within the end of fluid volume compensator 105. To prevent interference between the pin 100' and piston 55 when the latter is in a rear slide position in cylinder 52, the rear face of the piston is provided with a central recess 110 as shown.

Check valves 99 and 99' are urged toward the closed position by the combined force of their respective springs 102 and 102' and the hydraulic fluid in the cylinder acting on the inner face of their respective valve seats 101 and 101'.

The valves 99 and 99' are urged toward the open position by the hydraulic fluid in fluid return member 86 acting on the outer face of the respective valve seats 101 and 101' through the aforescribed system of orifices, grooves, etc. The faces of the valve seats 101 and 101' and the flexure characteristic of spring elements 102 and 102' are designed such that when the fluid pressure in cylinder 52 substantially equal that in fluid return member 86, valves 99 and 99' are held in the closed position and when the fluid pressure in cylinder 52 drops a predetermined level below the pressure in fluid return member 86, valves 99 and 99' are selectively caused to open.

The operation of the aforesaid static fluid orifices 92 and 93 and check valves 99 and 99' will now be described to illustrate the manner in which fluid return member 86 functions to prevent fluid cavitation in cylinder 52. For purposes of explanation it will be assumed that piston 55 when in a forward slide position in cylinder 52 is caused to accelerate rapidly rearwardly within cylinder 52 in response to a heavy buff force on coupler 7. It will be further assumed that the pressure differential between the front and rear ends of the cylinder at the outset of piston movement is of sufficient disparity that fluid cannot enter the front of the cylinder 52 through grooves 71 and through front static orifices 92 via fluid return member 86 and rear static orifices 93 fast enough to prevent cavitation within the front end of cylinder 52. When this happens, the pressure within the front of cylinder 52 drops below that within fluid return member 86 and as a result thereof, the net effective force tending to open check valve 99 increases. When the pressure differential reaches the predetermined level, check valve 99 opens allowing fluid to surge into the front end of cylinder 52 from fluid return member 86 in sufficient quantity to re-establish a continuous fluid condition therein. The setting of valve 99 is such that the above action occurs before any appreciable cavitation takes place in the cylinder and in this manner then, fluid cavitation in cylinder 52 with rearward movement of piston 55 therein is prevented. The rear check valve 99' acts in a similar manner to safeguard against fluid cavitation in the rear of cylinder 52 during forward sliding movement of piston 55.

In a piston type hydraulic system including the illustrated embodiment of the present invention, piston movement in the cylinder varies the length of the piston rod which is in the cylinder, thus varying the total available volume in the cylinder for the hydraulic fluid. Then too, the fluid in the system tends to change volume due to fluctuations in fluid temperature. The various metal parts of the system in contact with the fluid also tend to expand or contract as their temperature varies. In accordance with the present invention, such factors are compensated for and a completely filled fluid system is obtained without risk of high static fluid pressures, by the fluid volume compensator 105, shown in FIGS. 1, 2, 7 and 11. Compensator 105 includes a generally cup-shaped body 111 formed at its open end with a surround-

ing flange 112. The connection of the compensator 105 to the rear head 58 of cylinder 52 is effected in any suitable manner. As shown head 58 is formed with a flange 114 which mates with and is secured to flange 112 of compensator body 111 by a screw tensioned split clamp ring 115. Head 58 and body 111 form a housing which slidably receives a cup-shaped piston 116. An axially rearwardly extending pin 117 is secured to piston 116 in the center thereof and is slidably received within a tube or collar 118 formed integrally with the compensator body 111 to support the piston for sliding movement in the compensator 105.

Piston 116 is normally constrained toward a forward position in the fluid compensator 105 by a helical compression spring 119 seating between the piston 116 and the rear end of body 111. The sides of piston 116 are spaced from the sides of the compensator body 111 as shown and a flexible, fluid impervious diaphragm 120 is connected between the piston and body to seal the piston from the hydraulic fluid system. Diaphragm 120 has a main body portion 121 of circular design and is formed with a doubled-over marginal portion 122 extending normally of the plane of body portion 121 and which terminates in a wedge-shaped edge 123. The diaphragm fits over the front of piston 116 with marginal portion 122 projecting or disposed within the clearance between the piston 116 and compensator body 111. The wedge-shaped marginal edge 123 of diaphragm 120 is clamped within a complementary formed annular recess 124 defined by complementing annular grooves in the opposed and mating edges of body 111 and head 58, thus sealing the front of the compensator from the rear or piston conveying end thereof and providing a variable volume for hydraulic fluid in the compensator. Fluid communication between the front end of the compensator 105 and the hydraulic fluid system including the cylinder 52 and fluid return member 86 of the hydraulic unit 9 is established by providing head 58 with a passage 125 leading to drilled opening 107. The fluid connection is completed to cylinder 52 from passage 125 and drilled opening 107 by groove 106 and passage 108, fluid return member 86 and orifices 93 in the rear end of the cylinder 52 previously described.

In this manner, the cylinder 52 and fluid return member 86 are fluidly connected with the variable fluid volume source presented by compensator 105 to provide automatic adjustment for changes in the effective available volume in the cylinder and fluid return member for the fluid as well as changes in the total volume of fluid occurring in operation.

Referring now to the details of construction of return spring assembly 10, a pair of opposed compression spring elements consisting of a buff spring 126 and a draft spring 127 are mounted longitudinally of the coupler receiver assembly 8 and hydraulic unit 9 in outer board relation along each sill side wall 3 by an elongated rod 128. The front end of each rod 128 is connected to a front spring support bracket 129 secured across the bottom of coupler block 22 at the front end thereof, the bracket extending outwardly and clear of the sill proper in the assembly position of draft appliance as appears in FIG. 1. The front end of rods 128 is welded to a bearing plate 130 registering with and removably secured to a corresponding flange 131 on the outer ends of bracket 129 by a number of nut and bolt assemblies.

Buff springs 126 are mounted coaxially of each of rods 128 and are secured to bearing plate 130 at their forward ends by any suitable means. An intermediate spring support bracket 132 is secured across the bottom of housing 11 of coupler receiver assembly 8 approximately in line with housing rear end wall 14. The ends of bracket 132 are in longitudinal alignment with the ends of front bracket 129 and as clearly shown in FIG. 3 have an outwardly opening C-like construction through which the rods 128 extend. A centrally apertured spring

bearing disc or washer 133 is slidably received on the rods 128 immediately rearwardly of the intermediate brackets 132 and is resiliently held in backing engagement therewith by draft springs 127 to seat the rear ends of buff springs 126.

Draft springs 127 are mounted concentrically of each of the rods 128 at the rear ends thereof and engage washer 133 at the front ends. Rearwardly, draft springs 127 are seated by a washer and stop disc assembly 134 carried on the rear bracket 135 secured across the bottom of fluid return member 86 of hydraulic unit 9. Assembly 134 comprises a stop disc 136 rigidly connected to the rear end of each of rods 128, and forming an enlargement thereof, and a bearing washer 137 slidably mounted on the rods immediately forwardly of bracket 135 between disc 136 and the rear end of draft springs 127. The ends of rear bracket 135 are apertured to accommodate sliding movement of the rods 128 therethrough. Secured to the ends of bracket 135 and forming a forward extension thereof is a tubular spring seat 138 having an apertured end wall 139 slidably receiving the rods 128 and dimensioned to pass stop disc 136 but not washer 137.

In accordance with the invention, the draft springs 127 have greater flexure characteristic than buff springs 126 and normally hold bearing washer 133 intermediate bracket 132 and bearing washer 137 in engagement with end wall 139 of spring seat 138 against the opposed bias of buff spring 126 when the coupler and draft appliance are in an unloaded condition. Additionally, the springs 126 and 127 are of a length such that when assembled on rods 128 in the aforesaid manner each is in a pre-loaded state. The various parts of spring assembly 10 and coupler receiver assembly 8 are designed such that with springs 126 and 127 balanced against one another as aforesaid the coupler adapter block 22 is positioned well forwardly in housing 11 in what is the neutral position of the block (see FIG. 1). This position of block 22 in housing 11 results in piston 55 of hydraulic unit 9 being positioned well forwardly within cylinder 52 in the neutral position previously alluded to and described in connection with the hydraulic unit. Thus positioned, the block 22 and piston 55 have a relatively long stroke in the buff direction of movement, this being desirable due to the greater magnitude of the buff forces under normal conditions of operation.

The functioning of return spring assembly 10 is as follows. Assuming initially that the coupler 7 is subjected to a buff force, forcing coupler block 22 to slide rearwardly in housing 11 from neutral position. Initial rearward movement of block 22 causes the preloaded buff springs 126 to initially further compress against washer 133 as front bracket 129 slides rearwardly with the block, the washer 133 initially remaining seated on intermediate bracket 132 inasmuch as the draft springs are stronger than the buff springs. Rods 128 and stop discs 136 slide rearwardly with respect to rear bracket 135 with rearward sliding movement of block 22 while bearing washer 137 is fixed with respect thereto as it engages spring guide end wall 139, thus effecting the desired compression in buff springs 126. As block 22 continues rearwardly to further compress buff springs 126, the buff and draft springs eventually reach an equilibrium condition with respect to each other. At such time, washer 133 lifts off intermediate bracket 132 and both springs 126 and 127 undergo compression with rearward movement of block 22. When the force which is causing the coupler block to slide rearwardly in housing 11 is selected from coupler 7, buff and draft springs 126 and 127 return to their initial pre-compressed condition to thereby return block 22 to its initial or neutral position in housing 11 through their combined spring force. This in turn results in a corresponding return of piston 55 to its neutral position in the cylinder 52.

In the case of a draft load on coupler 7, coupler block

22 slides relatively forwardly in housing 11 from its normal position therein, causing the rods 128 to move forwardly. Stop discs 136 force bearing washers 137 forwardly against draft springs 127 with rod movement to compress the springs against washer 133 of the intermediate bracket 132. When the draft force is relieved from coupler 7, draft springs 127 extend to their original precompressed state to cause block 22 to return to normal position in housing 11 and thereby effect a similar return of piston 55 to the neutral position in cylinder 52.

The construction of the return spring assembly is highly advantageous in several respects. In the first place, the various support brackets of the spring assembly are integrated into the draft appliance proper and are completely independent of and separate from the sill proper. As a result, no separate attachments or detachments are required to be made between the return spring assembly and sill in the installation and removal of the draft sill appliance. This feature greatly facilitates and shortens the time to effect installation and removal of the appliance.

Further and referring particularly to FIGS. 2 to 4, the return spring assembly 10 is designed and constructed such that it is disposed in a horizontal plane below the plane of draft key 35 and in no way hinders or interferes with the removal and insertion of the key in the block in replacing a broken or damaged coupler. In this connection too, it will be noted that the front end of the coupler block 22 is recessed along the sides and that with the block in its normal position in housing 11, the lock pin 43 and retainer plate 41 holding draft key 35 in block 22 and exposed along the side of the latter as is the knock-out opening 36. This construction allows pin 43 and plate 41 to be readily removed and inserted when the block is in its normal slide position in housing 11. As a result of this design and further due to the fact that the spring assembly is in no way interconnected with the draft key, the draft appliance may be left completely intact during replacement of a broken or damaged coupler. A highly simple and fast method is thus provided by the present construction for replacing a defective coupler.

The overall operation of the draft appliance of the invention will now be described in connection with various different operations and conditions which it may experience when installed on a railroad car.

Assuming in the first instance that a car equipped with a draft appliance of the invention is part of a line of cars which is to be started from a stationary position and that the prime mover of the train is initially backed up to take out slack from between the cars and then driven rapidly forwardly to rapidly accelerate the individual cars. As the train backs up and slack is taken from the car under consideration, coupler 7 and coupler block 22 slide rearwardly until the rear stop face 26 of coupler block 22 engage the corresponding stop face 27 of housing 11, after which the rearward force is transmitted directly to the sill and car. The piston 55 is caused to slide rearwardly in cylinder 52 during the initial backup period and to the rearmost position therein simultaneously with the above. As a result, the full stroke of the hydraulic unit 9 is now available to absorb and dissipate the shock force on the car in question as it is jerked rapidly forwardly as the prime mover picks up speed. All damaging shock forces are absorbed by the hydraulic unit 9 due to the action of the previously described novel fluid flow system and the car and its loading are thus protected from damage in the starting of the train. Any unabsorbed shock force is transmitted into the sill and car through coupler block 22 and housing 11 via the front stops 24 and 25 of the block and housing respectively. Fluid cavitation in hydraulic unit 9 during the starting of the train is prevented by means of the check valve 99' in cylinder rear head 58, the operation of which has been previously discussed. In addition, the hydraulic unit 9 is protected

from overload as the car in question attains the speed of the prime mover by draft pressure relief valve 75.

Where the train is started without initially removing slack from the individual cars, only the draft stroke of the hydraulic unit is available to effect the shock dissipation. Under the above conditions, however, the shock force is much less severe and is applied more gradually.

In effecting coupling of railway cars provided with the draft appliance of the invention as by impact therebetween the hydraulic units of the appliances are initially in neutral position and at impact each unit is actuated towards buff position to effect a shock resisting action with respect to the impact force. In this case check valve 99 in front cylinder head 57 and the buff pressure relief valves 74 serve to preclude fluid cavitation and overload in each of the units to assure proper functioning thereof. Rear stops 26 and 27 of coupler block 22 and housing 11 respectively cooperate to transmit any unabsorbed force directly into the sill and car.

A similar shock resisting action and valve functioning in the hydraulic flow system is provided in the draft appliance of the invention when the car with which it is being used is subjected to bumping and jerking as the train is operated over curves and on grades and is otherwise decelerated and accelerated.

From the above described explanation, it can be seen that the draft appliance of the invention affords the car with which it is associated, a high degree of protection from the various shock loads to which it may be subjected in operation.

The integrated draft appliance of the invention is supported within the sill solely through the bolted brackets 18 and 21 and may be readily removed from and installed within the sill as a result thereof. Repair and maintenance of the appliance is greatly expedited by the present construction. The proposed design further permits the ready replacement of a coupler when required to overcome a serious problem in this respect. In addition to these and other features, the present invention provides an extremely compact and rugged shock absorbing unit which is well adapted to take up the various forces on railway cars.

With regard to the mounting of the proposed draft appliance in the center sill of a railway car, it will be appreciated that in the sill construction specified herein the extreme end of the sill and more specifically that portion ahead of the rear sill abutments 15 represents a departure from the usual sill design. To adapt a standard sill so that it may accept the draft appliance of the invention, and referring now to FIG. 12 illustrating one form of a sill of conventional design, the striker plate 140 of the standard sill 141 is initially removed as by cutting the rivets holding the plate in the sill. Everything is then removed from within the sill 141 including internal lugs, if present, and the pre-existing draft appliance. The sides of the standard sill are then cut away along their front edges in the manner indicated in FIG. 13, leaving the top of the sill intact as shown. A separate hat-section sill extension 142 which is preferably a cast construction is fabricated with the requisite offset sides and internal abutment surfaces described earlier and with the edge configuration on the sides thereof required to mate with the corresponding cut-away sides of the standard sill previously described. The sill extension 142 is then mated to the cut-away end of the standard sill 141 and secured thereto as by welding. To strengthen and rigidify the sill modified in this manner, sill extension 142 may be formed with a top abutment wall 143 adapted to abut the end of the railroad car with which the sill is associated. Various stiffening ribs may also be formed in sill extension 142 to increase its strength. This modification of a conventional sill may be effected fairly readily and renders the proposed draft appliance capable of wide-scale application in the railroad industry.

A second embodiment of the invention is illustrated in

FIGS. 14 to 18 of the drawings. This embodiment of the invention is particularly adapted for use with railway cars exceeding 60 feet and which are required to use the long shank A.A.R. alternate standard "E" and "F" type couplers. The long shank type coupling is considerably longer than the standard "E" coupler and, among other distinctions, is required by code to have an increased swing radius in the horizontal plane. In some instances, too, the long shank type coupler is required by industry to have lateral springing for automatic centering of the coupler in the sill in the horizontal when not otherwise restrained. When the long shank coupler is of the "F" tightlock head type, it becomes necessary to provide for vertical swing in addition to the lateral swing. With the tightlock coupler it is also necessary to provide a spring means below the centerline of the coupler for vertical support thereof.

Referring to FIGS. 14 to 18, the illustrated draft appliance 144 is adapted to be carried within a railway car center sill 145 (shown in phantom) in operatively coupled relation with a coupler 146 (also shown in phantom). Sill 145 differs in construction from the sill construction described in connection with the earlier embodiment of the invention in that it extends somewhat further out from the end of the car with which it is associated and is formed with a fish-mouthed or widened and dropped end portion.

The draft appliance is formed generally of a self-contained coupler receiver assembly 147, a two-way acting hydraulic shock absorber unit 148 connected with assembly 147 and a return spring assembly 149 connected between assemblies 147 and 148 for maintaining the appliance in a predetermined neutral position during no-load conditions therein. The construction and functioning of the components 147, 148 and 149 are much the same as the corresponding parts of the earlier embodiment of the invention and these parts are described only generally herein save for such features which differ or are additional.

Coupler receiver assembly 147 includes a housing 150 formed with spaced abutments interlocking with similarly spaced and formed abutments in the sill 145 to releasably lock the housing longitudinally therein. As best viewed in FIG. 15, the sill abutments in this form of the invention are located well to the rear of the front end of the sill as is the front of the housing. Secured to the sides of housing 150 at the front end thereof are a pair of support brackets 151 of right angle construction. Brackets 151 fit upwardly under and are removably secured to a flange 152 on either side of the sill to support housing 150 and the front end of the integrated draft appliance vertically in the sill.

A coupler adapter block 153 having an enlarged rear end or head 154 is slidably disposed in housing 150. The head 154 defines front and rear stop surfaces cooperating with longitudinally spaced front and rear stop surfaces formed interiorly of housing 150 to limit forward and rearward sliding movement of the block in the housing as in the previous form of the invention.

In this embodiment of the invention, coupler adapter block 153 is formed integrally with a forwardly extending coupler support structure 155 for supporting the coupler 146 adjacent the front end thereof in the vertical to decrease the moment forces thereon from vertically applied loads. A cross bar 156 extends across the end of the sill at the dropped portion thereof to slidably seat the coupler support 155 as appears in FIG. 14. Coupler support structure 155 includes a hollow rectangular deck-like platform 157 secured to the front lower edge of block 153. A transverse opening 158 is provided in the top wall of the platform 157 and a vertically reciprocal spring loaded bearing plate 159 is mounted for limited movement therethrough. The platform opening 158 is enlarged centrally of the top wall of platform 157. The plate 159 is formed with a flat, upper bearing sur-

face 160 and downwardly extending integral legs 161 are provided at the front and back edge centrally of the plate 159 and in alignment with the enlargement of opening 158. The legs 161 terminate in horizontal ledges 162 which engage upwardly against a pair of lateral bars 163 removably connected as by screws to a pair of elongated longitudinal bars 164 engaging under the top wall of the platform at the front and back of platform opening 158.

Bearing plate 159 is in this manner connected to the platform 157 for vertically reciprocal movement thereto. This is accomplished through structure permitting the ready separation of the bearing plate 159 and platform 157, it being necessary only to detach the lateral bars 163 from each of the longitudinal bars 164 to free the plate 159. Ready replacement or repair of the bearing plate is thus possible.

The bearing plate 159 is urged to normally raised position in platform 157 to provide a continuous vertical support for the coupler by a plurality of coil springs 165, six of which are shown in the illustrated construction. The springs 165 are arranged in a pair of transverse rows and are located at the ends by the aligned embossments 166 and 166' formed interiorly of the bottom wall of platform 157 and along the underside of plate bearing surface 160 respectively.

The provision of coupler support 155 on block 153 results in reduced bending loads in the coupler from loads applied downwardly with respect thereto. Further, by forming coupler support 155 integrally with block 153, the coupler 146 and coupler support 155 are maintained in the same relative position with respect to one another to maintain the coupler moment arm at a minimum at all times.

The coupler 146 which is of long shank type design extends within the chambered front end of coupler block 153 and is removably connected thereto by a vertical shank pin 167. To receive pin 167, the top and bottom surfaces of block 153 are formed interiorly with the opposed and apertured embossments 168 and 168', defining a vertically extending opening 169 in the block. Shank pin 167 fits through a slotted portion of the coupler shank 170 to connect the coupler to the block. Opening 169 is closed at the top by a circular end plate 171 which is countersunk in and secured to the top of the block as by welding, thus precluding shank pin 167 from upward movement in opening 169. The shank pin 167 is releasably held against downwardly movement in the opening 169 by a flat retainer plate 172 slidably received within a horizontally extending transverse slot 173 provided adjacent the bottom of block 153. Retainer plate 172 in turn is removably held in slot 173 by a pin 174 extended vertically through the lower block embossment 168' adjacent the side of the block and which projects into a slot 173 at one end of retainer plate 172. The upper end of pin 174 is headed while the lower end thereof is provided with a suitable cotter key to hold the pin captive in the block. The end of slot 173 opposite that to the pin 174 terminates short of the corresponding side of coupler block 153 as clearly shown in FIG. 15, thus locking retainer plate 172 in the slot 173 and releasably holding shank pin 167 captive in opening 169.

To provide for the ready withdrawal of retainer plate 172 from the block when it is desired to remove shank pin 167 from between the coupler 146 and the block 153, the side of the block adjacent the closed or blind end of slot 173 is provided with a knock-out opening 175 enabling plate 172 to be driven out the open end of the slot by a suitable implement when pin 174 is withdrawn. Further, the sides of the coupler block are provided with the relatively large access openings 176 to provide for the removal of pin 174 through the side of block 153 when it is driven upwardly out of embossment 168'.

The A.A.R. standards require the long shank type coupler to have a relatively wide radius of movement

with respect to the sill and car in horizontal plane to enable the longer cars with which the coupler is used to negotiate curves, grades and the like. When the "F" type head is used, movement is provided in the vertical plane also.

The swing movement of the coupler is accommodated when the parts are in the full pull-out position by well known construction and which includes a pin bearing block 177 disposed in the slotted portion of the coupler shank 170 in backing engagement with shank pin 167. In general, the front surface of block 177 is formed complementary to shank pin 167 while its rear face and the corresponding face of the shank slot are formed with complementary segmental spherical contours whereby the coupler 146 may pivot laterally and vertically with respect to the pin bearing block 177. The front face of the coupler shank slot is spaced from shank pin 167 and is shaped as shown in FIG. 14 to accommodate this movement of the coupler.

In full inward or buff position of coupler 146 swing movement of the coupler in both planes is accommodated through means of a spherical bearing assembly 178 provided between the rear end of coupler shank 170 and the inner end wall of the chambered portion of coupler block 153. In accordance with the invention, the bearing assembly 178 is designed and constructed to additionally provide automatic centering of the coupler in the appliance in the lateral or horizontal plane of movement to maintain the coupler in coupling position for effecting interconnection with the coupler of another car.

Referring to FIGS. 14, 15 and 17, the spherical bearing assembly 178 comprises a bearing plate 179 fixedly supported in a recessed portion of the coupler block 153 by any suitable means such as a press fit. The front face of plate 179 is curved arcuately inwardly on a vertical axis. Seated between the rear end of coupler shank 170 and bearing plate 179 is a follower block 180, the rear face of which is formed complementary to the corresponding front face of bearing plate 179. The front face of follower block 180 is provided with a concavely segmental spherical surface contour bordered or bounded on each side by a vertically extending flat surface 181 and by a flat wing-like extension 182. The rear end of coupler shank 170 is formed complementary to the front of follower block 180 and includes the flat side surfaces 183 engaging the surfaces 181 of follower block 180 as best viewed in FIG. 15. The bearing assembly 178 further includes a pair of compression springs 184 mounted horizontally within the coupler adapter block 153 one to either side of center and which extend forwardly to engage the wing-like extensions 182 of follower block 180 to maintain the latter in following relation with coupler shank 170.

By reason of the above described construction and arrangement of the parts in the assembly 178 and referring initially to coupler movement in the vertical plane, the rear end of coupler shank 170 floats vertically with respect to follower block 180 and the latter moves vertically in a corresponding direction relatively of bearing plate 179 to provide bearing support for the coupler in the vertical direction of movement. The coupler adapter block 153 is provided with the recessed portions 185 to accommodate this movement of the follower block 180 as shown in FIG. 14. In the case of lateral or horizontal pivoting movement of the coupler 146, the rear end of coupler shank 170 and follower block 180 pivot as a unit about bearing plate 179 owing to the engagement of the flat surfaces 181 and 183 to provide bearing support for the coupler during horizontal swing movement. In any such pivoting of the coupler the action of the follower block 180 moving with the coupler 146 results in an increased compression in the spring 184 on the side to which the coupler is pivoted. Thus, when the coupler is free of external resilient such as when it is detached from the coupler of another car either of the springs 184

if in a compressed condition as a result of the coupler being in an over center position will return follower block 180 to a centered position in the bearing assembly 178 to effect return of coupler 146 to a centered position in the appliance and sill.

A compact and relatively simplified structure is thus provided for accommodating the desired coupler movement in the vertical and horizontal planes while at the same time providing automatic centering of the coupler in the horizontal.

The shock absorber unit 148 for dissipating coupler forces is substantially identical in construction and functioning to the previously described unit 9 as is the interconnection of the unit 148 to the housing 150 and coupler adapter block 153 of the coupler receiving assembly 147. A somewhat different fluid orificing is employed in hydraulic unit 148 from that previously described in that the fluid return means in this embodiment comprises a pair of identical tube-like members 186 secured on either side of the top of the cylinder 187 of the unit 148 as opposed to the channel-section member 86 of unit 9.

One of the members 186 is shown rotated out of position in FIG. 14 and is broken away and sectioned to illustrate the interior thereof. Members 186 are in fluid communication with the front end of cylinder 187 through a pair of static orifices 188 (only one of which is shown in the drawings) in the top upper part of the cylinder and are in fluid communication with the grooved periphery of the front head 189 of the cylinder by a pair of orifices which are not shown but which are identical save for their location to orifices 96 of the previously described unit 9.

Fluid communication between each of members 186 and the rear end of cylinder 187 is provided by a pair of drilled radial openings 190 provided in the rear head 191 of cylinder 187 as shown in FIGS. 14 and 18, the head 191 in this instance being secured directly to and in effect forming a part of a fluid volume compensator 192 which is otherwise identical in construction with the compensator 105 described previously.

Drilled openings 190 are in direct two-way fluid communication with the rear of cylinder 187 by the passages 193 provided in the upper portion of head 191 and are in one-way fluid communication with the cylinder by a common passage 194 disposed in head 191 at the center thereof. A check valve 195 which is substantially identical in construction and operation to check valves 99 and 99' previously described is disposed in passage 194. A further pair of passages 196 in cylinder head 191 lead from the drilled openings 190 to the interior fluid volume of compensator 192, thereby establishing fluid connection between cylinder 187, compensator 192 and fluid return members 186.

Hydraulic unit 147, as stated, functions identically with unit 9, the various structural changes noted above between the units 147 and 9 providing one form of an alternative construction for the hydraulic unit.

The return spring assembly 149 of draft appliance 144 function in the manner previously indicated in the embodiment of FIGS. 1 to 11 to maintain the coupler block 153 and the hydraulic unit 148 in corresponding predetermined neutral positions during an unloaded condition of the coupler and draft appliance. In this embodiment, however, spring assembly 149 is mounted along the underside of the draft appliance and in lieu of the double or dual buff and draft spring system previously described is formed of a single set of buff and draft springs.

Referring to the details of construction of assembly 149, the front end of coupler adapter block 153 is shown having a depending arm 197 located on the underside of the block 153 just to the rear of the coupler support member 155. A bifurcated spring support bracket 198 is connected to the lower end of arm 197 by a pin 199 having a head and cotter key arrangement to hold the pin captive between the arm 197 and bracket 198. The

front end of a spring mounting rod 200 is secured to bracket 198 as by welding and mounts a pair of concentrically telescoped buff compression springs 201 seating forwardly against bracket 198. Rearwardly, buff springs 201 seat against a bearing washer 202 slidably mounted on rod 200 and which is yieldingly maintained in backing engagement with an intermediate spring support bracket 203 secured in depending relation on the front end of hydraulic unit 148 by a draft compression spring 204 disposed coaxially on the rear end of rod 200. For a purpose to appear, bracket 203 has a downwardly opening C-construction.

As in the previous construction, the rear end of draft spring 204 is provided with a forwardly moveable, rearwardly fixed support structure including a bearing washer 205 slidably mounted on the rear end of rod 200, a stop disc 206 fixedly secured thereto and a rear spring support bracket 207 fixedly secured in depending relation from the rear of hydraulic unit 148. Bracket 207 has an attached centrally apertured, tubular spring guide 208 preventing rearward movement of bearing washer 205 but not stop disc 206 with rearward movement of the rod 200.

The buff and draft springs of assembly 149 are pre-loaded and the draft spring employed has a stronger flexure characteristic than the collective flexure characteristic of the buff spring to maintain the parts in the position shown in FIGS. 14 to 16 during an unloaded condition of the coupler.

The functioning of the return spring assembly 149 is identical with that of return spring assembly 10 previously described and a description thereof is not provided for this reason.

It will be observed that in this embodiment of the invention the removal of shank pin 167 from coupler block 153 is normally precluded by the return spring assembly 149, it having been noted previously that the pin 167 is removed through the bottom of the block. However, the design and construction of the return spring assembly 149 set forth is such that pin withdrawal as well as its subsequent insertion within the block may be effected fairly quickly and easily. More particularly, to permit shank pin removal from the block 153, the spring return assembly 149 is first detached from the front spring support bracket 198 by knocking out the pin 199 between the arm 197 and bracket 198. Then, while holding bracket 198 in place against the preload of the buff and draft springs, the front end of the spring assembly 149 is dropped an amount sufficient to permit shank pin 167 to be removed through the bottom of the block 153. This dropping of the spring assembly 149 is possible as intermediate bracket 203 opens to the bottom of the appliance and sill as previously indicated. At the rear bracket 207, spring guide 208 is designed to provide a slight clearance with bearing washer 205 and stop disc 206 to enable the latter parts to move angularly therein as required to permit the necessary dropping at the front end of the spring assembly 149.

To reconnect the spring assembly, it is only necessary to lift the front end thereof to arm 197 and reinsert pin 199 between the arm and bracket 198.

A fairly simple and fast procedure is thus provided for displacing the return spring assembly to a position permitting shank pin removal from the coupler block and for reconnecting the assembly operatively within the draft appliance. This together with the previously described procedure by means of which the retainer plate 172 holding the shank pin 167 in the block 153 is removed and inserted enables the rapid removal and replacement of a coupler associated with the draft appliance if broken or damaged despite placement of the spring assembly on the underside of the appliance.

The integrated draft appliance of this embodiment of the invention is supported vertically within sill 145 at the front end by the support brackets 151 attached to the

sides of the housing 150 of the coupled receiver assembly 147 as previously described. Vertical support for the rear end of the appliance is provided by the rear spring support bracket 207 which to this end is formed with the laterally outwardly extending bracket-like portions 209 along the sides thereof. The bracket portions 209 engage the underside of sill flanges 152 and are removably connected thereto by suitable mounting bolts (not shown). The need for separate brackets as such for holding the rear end of the appliance in the sill is thus eliminated enabling a somewhat simpler all-around construction for the draft appliance.

The self-contained draft appliance of FIGS. 14 to 18 affords the same general structural advantages and design features set forth in connection with the earlier embodiment of the invention while incorporating various additional features adapting the appliance for use with long shank type couplers of railway cars. These latter features provide means for maintaining a fixed vertical support in the appliance for the front end of the coupler to minimize bending loads on the latter and for obtaining automatic centering of the coupler in the appliance and sill through novel bearing structure between the coupler adapter block and coupler. The underslung return spring assembly of the embodiment of FIGS. 14 to 18 while initially interfering with coupler detachment from the draft appliance is adapted to be detached from the appliance and moved to a position permitting coupler detachment with minimum expense of time and effort. The subsequent repositioning of the assembly in the appliance and reconnection thereto may be similarly readily performed.

FIGS. 19 to 21 illustrate a further modified form of the invention and which is comparable with the embodiment of FIGS. 1 to 11 in that it is designed for use with the A.A.R. standard "E" type coupler. In this form of the invention, however, the return spring assembly is mounted along the underside of the appliance rather than along the opposed sides thereof as previously described. In this form of the invention also, the spring assembly has a novel collapsible construction designed to reduce clearance requirements between the appliance and the wheel structure and other parts of the railway car in the operative position of the appliance in the center sill of such car. This is of particular importance in the case of a draft appliance designed for use with railway cars having the standard "E" type coupler as generally there is only a relatively short overhang at the ends of the car with respect to the wheel structures thereof and hence only a limited space is present in the car for installation of the appliance.

Only so much of the draft appliance as is needed to fully understand the construction of the spring assembly is shown in FIGS. 19 to 21. It will be understood, however, that except for minor and non-essential changes the construction is identical with that previously set forth in the description of embodiment of FIGS. 1 to 11. The fragmentary portion of the draft appliance 210 illustrated includes a coupler receiver assembly 211 having in combination a housing 212 and an interfitting slideable coupler adapter block 213. The block 213 and housing 212 are essentially constructed and designed to operate in the manner previously indicated in connection with coupler receiver assembly 8 of the earlier embodiment of the invention. A shock absorber mechanism 214 shown partially in FIG. 21 is connected to the inner end of housing 212 and is attached to the rear end of block 213 by an operating rod 215.

The return spring assembly indicated generally at 216 is formed of separate, identical sub-units disposed in longitudinally extending side-by-side relation along the underside of the appliance and, while only one such sub-unit is shown and described in detail herein, it is to be understood that the showing and description is applicable to both sub-units. The illustrated return spring sub-unit

216 comprises a front spring support bracket 217 secured in depending relation to the front end of coupler block 213. As shown in FIG. 20, bracket 217 is formed integrally with the identical plate portions 218 disposed to either side of the longitudinal centerline of the appliance. Secured at the front end to each of plate portions 218 in longitudinally rearwardly extending relation is an elongated spring mounting rod 219 having the telescopically interfitting front and rear sections 220 and 221 respectively. Front rod section 220 has a bearing plate 222 secured as by welding to its front end and the plate 222 is secured as by bolts or the like to plate portion 218 of front bracket 217 to support rod sections 220 in place. A pair of buff compression springs 223 assembled concentrically of one another is mounted coaxially of each rod section 220 with the spring 223 seating forwardly against bearing plate 222.

The inner end of front rod section 220 is slidably received within the front end of rear rod section 221, the latter having a tubular construction for this purpose. A bearing washer 224 is slidably mounted on rear rod section 221 to seat the rear end of buff springs 223. As in the previous embodiments of the invention, the bearing washer 224 is immediately behind and yieldingly held forwardly against an intermediate spring support bracket 225 dependently secured to the front of housing 212 by a draft compression spring 226 mounted coaxially of rear rod section 221. To this end, the intermediate bracket 225 is formed with the generally downwardly opening C-like half-sections 227 which are adapted to be engaged by bearing washer 224 under the bias of draft spring 226 to limit forward sliding movement of the washer 224 on its associated rod section 221. The rear end of draft spring 226 is seated against a rear bearing washer 228 threadably connected to the rear end of rod section 221 and forming an enlargement thereof, as shown. Bearing washer 228 and rear rod section 221 are fixed against longitudinally rearward movement with respect to a predetermined position by a rear spring bracket 229 secured in depending relation from the rear end of housing 212. Washer 228 is disposed immediately forwardly of bracket 229. As in the case of brackets 217 and 225, bracket 229 is formed with the separate but integral half-sections or portions 230 to either side of the longitudinal axis of the draft appliance and each section 230 has a tubular spring guide 231 forming a forward extension of the bracket and secured to its front face by any suitable means. Guide 231 is adapted to slidably receive bearing washer 228 on the rear end of rod section 221 and cooperates therewith to provide stop means for limiting rearward sliding movement of rod section 221.

As in the previous forms of the invention, draft spring 226 has a stronger flexure characteristic than the combined flexure characteristics of the pair of buff springs 223 which it opposes and normally holds bearing washer 224 in backing engagement with intermediate bracket 225 and bearing washer 228 in engagement with spring guide 231 against the opposed bias of buff springs 223 with spring assembly 216 in a balanced state. In addition, the flexure characteristic of springs 223 is selected such that with return spring assembly 216 in a balanced condition the net effective bias force tending to cause coupler block 213 to slide forwardly in housing 212 is sufficient to maintain block 213 in a normally forward position therein, this then being the neutral position of the coupler block. The shock absorber unit 214, in turn is positioned in a corresponding neutral position in its operating stroke by the spring assembly 216 acting through block 213 and operating rod 215.

The operation of the return spring assembly 216 when coupler block 213 is caused to slide in housing 212 in either direction from neutral is substantially identical to that previously described for the return spring assemblies 10 and 149 of the previous embodiments of the invention. However, in the case of spring assembly 216, as

block 213 slides rearwardly from the neutral position, front rod section 220 of each of the sub-units of return spring assembly 216 telescopes within its corresponding rear rod section 221 and the latter remains in a longitudinally fixed position. This is in contradistinction to the earlier described and illustrated constructions wherein the spring mounting rods being of one-piece construction passed through the rearmost bracket of the spring assembly with rearward movement of the coupler block an amount commensurate with the movement of the block. In these constructions then, it is necessary to have a predetermined amount of clearance between the end of the appliance and the associated parts of the railway car with which the appliance is being employed on the plane of the springs. The telescopic construction of rods 219 employed in spring assembly 216 eliminates this requirement and enables mounting of the spring assembly along the underside of the appliance in applications wherein such disposition is normally prevented due to lack of the necessary clearance with the associated parts of the railway car as is generally the case in cars of from 50 to 60 feet in length.

In order to effect the desired compression of the draft spring elements 226 with movement of block 213 in housing 212 forwardly of the neutral position, the sections 220 and 221 of the rods 219 are constructed to define a suitable annular clearance between their interfitting ends. Disposed in such clearance and secured to the inside of rear rod section 221 at the front end is a sleeve 232. A corresponding sleeve 233 is secured to the rear end of front rod section 220 and extends toward and abuts sleeve 232, as shown, whereby the sections 220 and 221 move as a single unit in response to forward sliding movement of coupler block 213. As a consequence, the rear bearing washer 228 moves forwardly with rod section 221 as block 213 slides forwardly of neutral position to effect compression of draft springs 226 between the forward and rearward bearing washers 224 and 228 respectively.

In the embodiment of the invention illustrated in FIGS. 22 and 23, a fragmentary portion of a draft appliance 234 of the type designed for use with a long shank coupler and which is alike in construction and operation to the embodiment of FIGS. 14 to 18 is shown incorporating an underslung return spring assembly 235 having a dual or double set of side-by-side spring elements. The spring assembly 235 is substantially identical in construction to that of spring assembly 216 just described and for present purposes a further description thereof is not needed. The provision of spring assembly 235 in a draft appliance adapted for use with a long shank coupler is highly advantageous in that by disposing the separate spring sub-unit to either side of the longitudinal axis of the appliance the vertical shank pin 236 for connecting the coupler 237 to the coupler block 238 may be removed from or inserted within the block through the space defined between the spring sub-assemblies. As opposed to the previous construction of FIGS. 14 to 18 employing a single set of spring elements disposed along the longitudinal centerline of the appliance, this construction greatly simplifies and facilitates coupler removal and replacement and from this standpoint represents an important and desirable feature.

The novel self-contained draft appliance set forth herein functions independently of the sill within which it is mounted in taking up and absorbing coupler shock forces and in transmitting any unabsorbed portion of a shock force to the sill. As a result, all wearing from friction and from impact between parts is confined to the appliance proper. The mechanical stop system provided in the appliance for limiting the operating stroke thereof in the buff and draft directions of movement enables close control over the stroke by manufacture to insure the desired functioning of the appliance. The proposed draft appliance has a highly simplified mounting within the center sill of the railway car with which it is employed and, in the appliance itself, the parts thereof are arranged in a manner

permitting their convenient disassembly and assembly. The shock absorbing mechanism proposed for use in the draft appliance has a compact and rugged construction and an efficient and reliable operation and by reason thereof contributes importantly in providing structural compactness and operational efficiency in the appliance proper.

The various other features and innovations enumerated in the several embodiments of the invention render the appliance suitable for application to varying types of couplers and railway cars to further enhance the overall desirability of the proposed draft appliance.

Various modes of carrying out the invention are contemplated as being within the scope of the following claims particularly pointing out and distinctly claiming the subject matter which is regarded as the invention.

I claim:

1. A self-contained draft appliance for mounting within a downwardly opening center sill of a railway car and for supporting a coupler of the car which comprises: a housing adapted to be fixedly secured adjacent an open end of the sill, a coupling adapter block slidably disposed in said housing, means disposed within the confines of said block to releasably receive a coupler, shock absorbing means including a cylinder forming an inward extension of said housing and a piston connected to the inner end of said coupling adapter block to absorb draft and buff shock forces transmitted to the latter from the coupler, resilient return means connected between said adapter block and said housing and disposed beneath the latter and urging said block to an intermediate neutral slide position in said housing and so that said piston is disposed between the ends of said cylinder, stop means within said housing to limit the fore and aft movement of said adapter block, and means disposed externally of said housing for cooperating with said sill to prevent longitudinal movement of the housing relative to the sill.

2. The draft appliance of claim 1 in which said stop means comprises: an enlargement forming the inner end portion of said adapter block, and vertically extending front and rear abutment surfaces disposed internally of said housing, said surfaces being disposed in the path of the enlarged portion of said adapter block.

3. The draft appliance of claim 2 in which said front and rear abutment surfaces are so positioned relative to said cylinder and piston that draft or buff forces will cause said enlargement to strike the respective surface so that the respective force will be transmitted to said sill through said fixed housing at termination of the full stroke of said enlargement.

4. The draft appliance of claim 1 in which the means within the said block to releasably receive a coupler comprises: a transverse slot disposed in said block and with said slot having a closed end and an open end, a shoulder disposed in said slot and slightly inwardly from said open end, a draft key disposed in said slot and held against transverse movement between said closed end and said shoulder, a retainer plate disposed above said key in said slot and extending to said open end, a retainer pin extending through said plate and said slot outwardly of said shoulder, and said housing having an opening therein adapted to be aligned with said open end of said slot for insertion and removal of said draft key therethrough.

5. The draft appliance of claim 1 in which the said resilient return means comprises: a front bracket connected to the outer end portion of said coupling adapter block, a central bracket and a rear bracket secured to said housing and with each bracket having an opening therein, a rod connected to said front bracket and extending rearwardly through said central bracket to said rear bracket, a first washer slideably mounted on said rod and larger than the opening in said central bracket and disposed immediately rearwardly of the latter, a second washer slideably mounted on said rod and larger than the opening in said rear bracket and disposed immedi-

ately forwardly of the latter, a first compression spring mounted concentrically on said rod and seated between said front bracket and said first washer, a second compression spring having a greater flexure characteristic than said first spring and mounted concentrically on said rod and seated between said first and second washers, and said rod having an enlarged rear end portion disposed rearwardly of said second washer and with said enlarged portion being of a size so that it can move in said rear bracket opening but cannot pass through said second washer; the construction being such that as said adapter block slides rearwardly from said neutral position under buff load, said first spring is compressed between its seats and said first washer is moved rearwardly under heavy loads to compress said second spring between its seats and as said adapter block slides forwardly from neutral position under draft load, the enlarged portion of said rod moves said second washer forwardly to compress said second spring against said first washer.

6. The draft appliance of claim 5 in which at least one of said central and rear brackets opens outwardly to permit removal of said rod therethrough upon disconnection of said rod from said bracket.

7. The draft appliance of claim 1 in which the said resilient return means comprises: a front bracket connected to the outer end portion of said coupling adapter block, a central bracket and a rear bracket secured to said housing and with said central bracket having an opening therein, a front rod connected to said front bracket and extending rearwardly therefrom, a rear rod telescopically disposed with the rear end of said front rod and extending rearwardly to adjacent said rear bracket, a washer slideably mounted on one of said rods and larger than the opening in said central bracket and disposed immediately rearwardly of the latter, said rear rod having an enlarged rear end portion disposed immediately forwardly of said rear bracket and adapted to seat rearwardly thereagainst, a first compression spring mounted concentrically on said front rod and seated between said front bracket and said washer, a second compression spring stronger than said first spring and mounted concentrically on said rear rod and seated between said washer and said enlarged end portion of said rear rod, an annular clearance being provided between the telescoping portions of said rods, and an annular sleeve secured to the end portion of each said rod with the sleeve of each rod extending in said clearance toward the sleeve of the other rod; the construction being such that as said adapter block slides rearwardly from said neutral position under buff load said rods telescope together and said first spring is compressed between its seats and said washer is moved rearwardly under heavy loads to compress said second spring between its seats, and as said adapter block slides forwardly from neutral position under draft loads said rods telescopically move apart so that said sleeves coengage so that both rods move forwardly together to compress said second spring between said washer and said enlarged end portion of said rear rod.

8. The draft appliance of claim 7 in which at least one of said central and rear brackets opens outwardly to permit removal of said rods therethrough upon disconnection of said front rod from said front bracket.

9. In a coupling mechanism of a railway car, a downwardly opening center sill disposed longitudinally on the underside of the car and defining an open ended draft gear pocket formed with longitudinally spaced vertically extending front and rear internal abutment surfaces disposed inwardly of the sill end, a coupler for interconnection with the coupler of another car and extending within the open end of said draft gear pocket, and a self-contained draft appliance extending longitudinally within said draft gear pocket, said draft appliance including: an external housing having longitudinally spaced vertically extending front and rear external abutment surfaces

engaging said front and rear internal abutment surfaces of said draft gear pocket to lock said appliance longitudinally therein, and shock absorbing means slideable within said housing for lockingly receiving said coupler.

10. A self-contained draft appliance for mounting within a downwardly opening center sill of a railway car and for interconnection with a coupler of the car for absorbing shock forces thereon, which comprises: a housing adapted to be fixedly secured adjacent an open end of the sill, a coupling adapter block slideably carried therein, means disposed within the confines of said block to receive a coupler, a shock absorbing cylinder and piston disposed rearwardly of said block and having a piston rod extending forwardly to said block, a vertically extending recess disposed in the rear end of said adapter block and with said recess forming a vertical shoulder at its upper end, and ball joint means disposed within the upper portion of said recess and normally engaging said shoulder and connecting the outer end of said rod with said block, said ball joint means being vertically slideable within said recess to enable ready detachment of said rod from said block.

11. In a coupling mechanism for a railway car: a downwardly opening center sill defining an elongate draft gear pocket open at one end, a lower cross bar mounted adjacent said open end of said sill, a housing fixedly secured within the end portion of said sill, a coupling adapter block slideably disposed within the confines of said housing, a coupler having an inner shank end releasably interconnected with the said adapter block and extending outwardly therefrom, said coupling adapter block projecting forwardly of the open sill end, and a bearing plate mounted on the forward projection of said block and underlying the shank of said coupler to reduce the moment arm of the coupler with respect to downwardly directed coupler loads, means resiliently biasing said plate upwardly against said coupler, said forwardly projecting portion of said block overlying and being slidably supported by said cross bar.

12. The appliance of claim 4 which includes: means for locking the said retainer pin in place.

13. In a self-contained draft appliance for mounting within a downwardly opening center sill of a railway car: a housing adapted to be fixedly secured adjacent an open end of the sill, a coupling adapter block slideably disposed in said housing and with said adapter block having an outwardly opening central chamber and a wall at the inner end of said chamber, a centrally disposed spherical bearing plate mounted in said wall, a movable follower block having a spherical bearing surface engaged with said bearing plate, said follower block having

a pair of radially extending vertical wing-like extensions, a coupler for securement to a railway car and extending through said chamber and engaging said coupler block, means to secure said coupler in said chamber for horizontal pivoting about the inner coupler end, and a spring disposed in said inner wall on each side of said bearing plate and engaging the respective wing-like extension of said follower block, said springs biasing said follower block and said coupler toward a normal central axial position.

14. In a draft gear appliance for railway cars: a fluid confining closed pressure cylinder member, a piston member slideably mounted in said cylinder, one of said members being movable relative to the other in response to application of draft or buff forces to the appliance, said cylinder being provided interiorly with a plurality of axially extending circumferentially spaced grooves forming a restricted flow path for the said fluid, said grooves being longer than the longitudinal extent of said piston and terminating in a common radial plane spaced from one end of said cylinder and extending with varying axial length toward the other cylinder end, and means for normally positioning and holding said piston so that it overlies said grooves and so that the piston end facing said one cylinder end lies in said common radial plane, relative movement so that said piston approaches the said one end of said cylinder from said normal position creating a relatively constant fluid pressure in said cylinder with no fluid passing through said grooves, and relative movement so that said piston approaches the said other end of said cylinder from said normal position creating a progressively increasing fluid resistance to piston movement due to the decreasing flow path through that portion of the grooves between said piston and said other end.

UNITED STATES PATENT OFFICE
CERTIFICATE OF CORRECTION

October 13, 1964

Patent No. 3,152,699

Hal E. Vickerman

It is hereby certified that error appears in the above numbered patent requiring correction and that the said Letters Patent should read as corrected below.

Column 6, line 54, for "kaye" read -- key --; column 14, line 68, for "selected" read -- released --; column 15, line 32, for "and" read -- are --.

Signed and sealed this 13th day of April 1965.
